UNITED STATES PATENT OFFICE.

B. D. LENHART ELLISON, OF EASLEY, SOUTH CAROLINA, ASSIGNOR TO DRAPER CORPORATION, OF HOPEDALE, MASSACHUSETTS, A CORPORATION OF MAINE.

THREAD-CUTTING TEMPLE FOR LOOMS.

Application filed June 8, 1925. Serial No. 35,556.

To all whom it may concern:

Be it known that I, B. D. LENHART ELLISON, a citizen of the United States, and a resident of Easley, county of Pickens, 5 State of South Carolina, have invented an Improvement in Thread-Cutting Temples for Looms, of which the following description, in connection with the accompanying drawing, is a specification, like characters 10 on the drawing representing like parts.

This invention relates to the thread cutting temple employed in looms for severing the filling ends left extending from the cloth at the selvage. Such instrumentalities usually comprise a movable cutter member which is actuated in one direction by or through the movement of the lay and in the opposite direction by a spring. A well known and widely used form of such a device is shown in the patent to Stimpson 15 #1,366,034, granted January 18, 1921.

The object of the present invention is to provide a construction which will minimize the wear between the actuating spring and the movable cutter member. The spring employed for actuating the movable cutter member is usually formed of steel wire and mounted or anchored at its upper end to the temple head, while its lower end is coiled 20 about a stud projecting laterally from the movable cutter member. The coils of the wire not infrequently wear into the stud to such an extent as to interfere with the proper operation of the device. This 25 deleterious wear occurs particularly when the projecting stud is formed of cast iron, due to its integrality with the cast iron type of movable cutter member.

The present invention enables the use of 30 the very practical and efficient wire spring to be maintained and at the same time eliminates any danger from excessive wear taking place between the spring and the stud by providing a sleeve secured to the 35 lower end of the wire spring, in place of the usual coiled end, which sleeve presents a smooth, cylindrical bearing surface fitting over the stud.

The nature and object of the invention 40 will appear more fully from the accompanying description and drawings and will be particularly pointed out in the claims.

As the present invention relates only to 45 one feature of the construction and operation of the thread cutting temple, which

otherwise is of a construction and operation well known to those skilled in the art, it is only necessary to illustrate and describe in detail the parts directly concerned with the invention. 60

The preferred form of construction illustrated is shown in connection with a thread cutting loom temple of the type disclosed in the above-mentioned patent to Stimpson. 65

In the drawings:

Fig. 1 is a side elevation of a temple embodying a preferred form of the present invention.

Fig. 2 is a detail on a larger scale partially in transverse cross section. 70

The temple, as usual, comprises a head 1, from which extends forwardly a shank 2 mounted to reciprocate yieldingly in the stand 3, which is usually secured to the breast beam of the loom adjacent the path of the selvage of the cloth. The head is provided with a depending heel 4, which is struck by the lay on the beat-up to give the forward bodily movement to the temple. 75

The thread cutting elements comprise a fixed blade mounted vertically in a slot opening at the rear face of the temple head and not here shown, and a movable blade with which the present invention is particularly concerned. This movable blade comprises a body portion 5, a hooked end 6 having a cutting edge 7 which cooperates with the fixed blade to sever the filling ends, 80

a depending heel 8 and a laterally projecting stud 9. When the movable cutter member is of the type shown in the Stimpson patent above-mentioned, it is formed in its 85 entirety of cast iron. This cutter member has a reciprocating and rocking motion in

a slot extending from front to rear through the temple head. The rearward movement of this member is usually effected by a spring and leaves the cutter member normally standing in the position shown in 90 Fig. 1. The forward movement, or that movement by which the cutting action is effected is caused by the lay on the beat-up striking against the depending heel 8 and carrying the cutter member forwardly 95 against the action of the spring. This operation is well known and familiar to those skilled in the art.

The actuating spring is formed of steel 100 wire 10. The upper end of this spring is 110

formed into a coil 11 which fits over a stud 12 projecting laterally from the head. The end 13 of the coil 11 is carried rearwardly and rests upon a shoulder 14 formed on the head. By this construction, which is that usually employed, the upper end of the spring is mounted upon or anchored to the head.

In the present invention, the lower end 10 of the wire 10 has secured thereto a sleeve. This sleeve 15 is formed of metal and is shown as having an upwardly projecting shank 16 in which the end of the wire 10 is rigidly secured. The sleeve presents a smooth, cylindrical bearing surface fitting over the stud 9, and this surface is of a length equal to several times the diameter of the wire of the spring 10, thus insuring a relatively long bearing upon the stud.

It is found in practice that the construction of this invention eliminates all danger of any substantial amount of wear taking place at the stud 9 because the sleeve 15 has a bearing fit throughout its length on the stud. Thus, even when the stud is formed of cast iron, due to its integrality with a cast iron cutter member, the desired results are secured in a simple, efficient and practical manner and all objections to the use of the otherwise highly desirable wire spring are removed.

While a specific form of sleeve has been illustrated in which the connection with the wire of the spring is effected through the medium of the upwardly projecting shank 16, it will be recognized that the invention is not to be restricted to the particular means employed for securing the sleeve to the wire of the spring.

Having thus described the invention, what is claimed as new, and desired to be secured by Letters Patent, is:

1. A thread cutting temple for looms comprising a head, a movable cutter member mounted in the head and provided with a projecting stud, and a wire spring for actuating the cutter member mounted at one end on the head and having secured to its other end a sleeve presenting a smooth, cylindrical bearing fitting over the stud. 45 50

2. A thread cutting temple for looms comprising a head, a movable cutter member mounted in the head and provided with a projecting stud, and a wire spring for actuating the cutter member mounted at one end on the head and having secured to its other end and fitting over the stud a sleeve presenting a smooth, cylindrical bearing of a length equal to several times the diameter of the wire of the spring. 55 60

3. A thread cutting temple for looms comprising a head, a cast iron movable cutter member mounted in the head and provided with an integral projecting stud, a wire spring for actuating the cutter member mounted at one end on the head and having secured to its other end a sleeve presenting a smooth, cylindrical bearing fitting over the stud. 65

4. A thread cutting temple for looms comprising a head, a cast iron movable cutter member mounted in the head and provided with an integral projecting stud, a wire spring for actuating the cutter member mounted at one end on the head and having secured to its other end and fitting over the stud a sleeve presenting a smooth, cylindrical bearing of a length equal to several times the diameter of the wire of the spring. 70 75 80

In testimony whereof, I have signed my name to this specification.

B D LENHART ELLISON.
